UNITED STATES PATENT OFFICE.

FERDINAND SCHMIDT, OF DES MOINES, IOWA, ASSIGNOR TO FRED C. REIMER CO. INC., OF NEW YORK, N. Y., A CORPORATION OF NEW YORK.

DESIGN FOR A GOBLET OR THE LIKE.

Application filed December 8, 1924. Serial No. 11,621. Term of patent 7 years.

To all whom it may concern:

Be it known that I, FERDINAND SCHMIDT, a citizen of the United States, and a resident of Des Moines, in the county of Polk and State of Iowa, have invented a new, original, and ornamental Design for Goblet or the like, of which the following is a specification, reference being had to the accompanying drawing, forming part thereof.

The figure is a side elevation of the goblet showing my new design.

The goblet, which is made of glass, is finished to impart thereto a crackled effect.

I claim:

The ornamental design for a goblet or the like, as shown and described.

FERDINAND SCHMIDT.
